PAPER CUTTING MACHINE

Viktor Schreckengost, Cleveland, and Russell I. Haywood,
Dayton, Ohio, assignors to Harris-Intertype Corpora-
tion, Cleveland, Ohio, a corporation of Delaware

Filed Aug. 31, 1962, Ser. No. 71,511

Term of patent 14 years

(Cl. D55—1)

FIG-2

FIG-1

FIG-3

FIG-4

FIG. 1 is a perspective view of a paper cutting machine, showing our new design;

FIG. 2 is a front elevation thereof;

FIG. 3 is a top plan view thereof with portions omitted for convenience of illustration;

FIG. 4 is a side elevation thereof with the support stand broken away in part to indicate indeterminate length.

The dominant features of the design are illustrated in full lines in the drawings.

We claim:

The ornamental design for a paper cutting machine, as shown and described.
